COMBINED ANIMAL AMUSEMENT DEVICE AND SHELTER

Mike Smirnow, 531 Pandora Ave. W., Transcona,
Manitoba, Canada

Filed Oct. 6, 1965, Ser. No. 87,341

Term of patent 3½ years

(Cl. D30—1)

FIG. 1 is a top plan view of a combined animal amusement device and shelter, showing my new design; and FIG. 2 is a side elevational view thereof.

The undisclosed side of FIG. 2 of the drawing is a mirror image of the side shown.

I claim:

The ornamental design for a combined animal amusement device and shelter, as shown and described.
